(57) **CLAIM**

The ornamental design for a display screen or portion thereof
with icon, as shown and described.

DESCRIPTION

The file of this patent contains at least one drawing/photograph
executed in color. Copies of this patent with color
drawing(s)/photograph(s) will be provided by the Office upon
request and payment of the necessary fee.

FIG. 1 is a front view of a display screen or portion thereof
with icon showing my new design; and,

FIG. 2 is a front view of a display screen or portion thereof
with icon showing an alternative embodiment of the new
design.

The broken lines shown in the drawings represent portions of
the display screen or portion thereof that form no part of the
claimed design.

**1 Claim, 1 Drawing Sheet
(1 of 1 Drawing Sheet(s) Filed in Color)**

FIG. 1

FIG.2
